CARTON

Clifford D. Fallert, St. Louis, Mo., assignor, by
mesne assignments, to Gaylord Container Cor-
poration, St. Louis, Mo., a corporation of
Maryland

Application November 6, 1935, Serial No. 48,489

1 Claim. (Cl. 229—33)

My invention relates to a carton and particularly to a one-piece carton formed of fiberboard or other bendable material suitable for storing and shipping bottled beer or similar merchandise.

5 The object of my invention is to provide a carton of the class referred to which will not only be simple in construction and inexpensive to manufacture but which will be strong and rigid, and more particularly to provide simple and effective means for reinforcing the ends of the carton.

In the accompanying drawing, which illustrates one form of carton made in accordance with my invention, Figure 1 is a vertical cross-section; Figure 2 is a section taken on the line 2—2 of Figure 1; Figure 3 is a plan view of the blank from which the carton is made; and Figure 4 is a section through one end of the carton, taken on the line 4—4 of Figure 1.

20 The carton is formed from a single sheet of fiberboard or similar material stamped out in the form shown in Figure 3. This blank is divided by longitudinal crease lines 1 into a central strip and two similar lateral strips. The central strip 25 is divided by transverse crease lines 2 and 3 into a bottom panel 4, a pair of side panels 5 and a pair of cover panels 6. The cover panels are each divided by transverse crease lines 7 and 8 into a side cover flange 9 and a flange lining 10. Carried by each of the cover panels are a pair of end flanges 11 terminating in tongues 12. The lateral strips are each divided by slots 13 into a central end panel 14 carried by the bottom panel 4, and two end panels 15 carried 35 by the side panels 5. Each of the panels 14 and 15 are provided with a hand-hole 16 and the panels 15 with a slot 17 so positioned that the holes and slots will be aligned when the panels 15 are superimposed upon the panel 14.

40 To form the carton from the blank the side panels 5 are first bent up at right-angles to the

bottom panel 4. The end panels 15 are now bent over at right-angles to the side panels 5 and the end panels 14 bent up against them, after which the end panels are secured together by staples 18 or other suitable fastening means. Each end of the carton is thus formed of three-ply material providing a very strong and rigid structure. The cover flanges 9 and 11 are now bent over at right-angles to the cover panels 6, the tongues 12 bent over against the inner faces of the flanges 9, and finally the lining strips 10 are folded over parallel with the flanges 9 enclosing the tongues 12 between the two parts and are secured in position by staples 19. Each of the cover panels is thus provided with a depending flange adapted to 15 enter the slots in the upper edges of the ends in a manner similar to that shown in my prior application Serial No. 14,008 filed April 1, 1935.

The side strips of the blank are of less width than the depth of the carton as determined by 20 the width of the side panels 5. Due to this, the inner plies of the ends formed by the panels 15 project above the outer ply formed by panels 14. Recesses are thus provided for the reception of 25 cover flanges 11 so that they may abut against the edges of the outer ply to produce a carton with flush ends.

Having fully described my invention, what I claim as new and desire to secure by Letters Patent of the United States is:

30 A carton comprising integral bottom, side and cover panels, a pair of end panels carried by the bottom panel, a pair of end panels carried by each side panel and each provided with a slot, said latter-named end panels overlapping and 35 projecting above said first-named end panels, and flanges on the cover panels, said flanges abutting the edges of the first-named end panels and entering the slots in the second-named end panels.

CLIFFORD D. FALLERT.
